UNITED STATES PATENT OFFICE.

JAMES O. BROWN, OF BOSTON, MASSACHUSETTS, ASSIGNOR TO HIMSELF AND JOSIAH QUINCY, OF SAME PLACE, AND JOHN R. GRAHAM, OF QUINCY, MASSACHUSETTS, TRUSTEES.

STREET-CAR EQUALIZER.

SPECIFICATION forming part of Letters Patent No. 549,763, dated November 12, 1895.

Application filed June 27, 1895. Serial No. 554,206. (No model.)

To all whom it may concern:

Be it known that I, JAMES O. BROWN, of Boston, in the county of Suffolk and State of Massachusetts, have invented certain new and useful Improvements in Street-Car Equalizers, of which the following is a specification.

This invention has for its object to provide simple and effective means for preventing the vertical oscillating movements of the bodies of street-cars upon the truck-frame; and it consists in the combination, with a car-body, a truck-frame, and body-supporting springs interposed between the body and frame, of an equalizing device comprising a rock-shaft journalized in bearings upon the truck-frame and extending longitudinally of the car, and positive or unyielding connections between said rock-shaft and the car-body, out beyond the wheels at both ends, whereby a vertical movement of either end of the car is transmitted through the rock-shaft to the other end of the car-body, so that independent vertical movements of either end of the body are prevented, the car-body being kept substantially parallel with the truck-frame.

Of the accompanying drawings, forming a part of this specification, Figure 1 represents a longitudinal section of a car-body and truck-frame provided with my improved equalizing device. Fig. 2 represents a section on line 2 of Fig. 1 and a plan view of the parts below said line. Fig. 3 represents an end view of the construction shown in Fig. 1.

The same letters of reference indicate the same parts in all the figures.

In the drawings, *a* represents the body of a street-car, and *b* represents the truck-frame, which is provided with the usual wheels *c* and supports the body in the usual or any suitable manner, suitable springs *d* being interposed between the said frame and car-body.

In carrying out my invention I provide an equalizing mechanism to keep the car-body substantially parallel with the truck-frame and prevent independent vertical movement of either end of the car-body. Said mechanism comprises two rock-shafts *e*, which are journalized in bearings *f* on the truck-frame and extend longitudinally of the car beyond the wheels, and suitable inelastic or inflexible

connections between the end portions of each rock-shaft and the car-body, which cause vertical pressure at either end of the car-body to be communicated through the rock-shaft to the other end of the car-body. Said connections, as here shown, comprise crank-arms *e'* *e'*, affixed rigidly to the ends of the rock-shaft, and links *e²* *e²*, connecting said arms with the car-body, as clearly shown in Fig. 3.

It will be seen that in a car provided with the above-described equalizing device the common so-called "teetering" movement of the car-body, causing its ends to oscillate vertically through arcs of considerable length, is prevented, the car-body being positively connected with the truck-frame by four positive connections which are variable in length and vary simultaneously, so that the distance between all parts of the car-body and the frame must necessarily be uniform.

I am aware that rock-shafts journalized on the truck-frame have been connected with a car-body by torsional springs, as in Reissued Patent No. 5,359; but such springs are not an equivalent of the inelastic or inflexible links which I employ, because they (the said springs) necessarily permit more or less independent movement of either end of the car, while the links which I employ in connection with the cranks and rock-shafts constitute positive connections, preventing such independent movement.

I am also aware that rock-shafts have been disposed transversely of the car-body in bearings on the truck and connected by links with the car-body for equalizing purposes to prevent sidewise tilting; but it is necessary to the accomplishment of my object that the equalizing-shafts extend longitudinally of the car-body, for the object is to prevent endwise tilting of the car, the invention being specially applicable to street-cars, wherein it is customary to have the body of the car project considerably beyond the wheels at both ends, giving a leverage productive of the endwise-tilting motion from comparatively slight causes.

It is not only necessary to the practical accomplishment of the object of my invention that the equalizing-shafts extend longitudi-

nally of the car-body, but it is highly important that they extend beyond the wheels, so that the link connections can be made outwardly beyond the centers of endwise up-and-down oscillation; and herein the invention involves more than the mere changing of the equalizing-shafts from transverse to longitudinal position, but effects a new relation of the parts of the vehicle to the parts of the equalizing mechanism and a novel combination, operating as such to produce a new effect.

I claim—

1. The combination with a car-body, a truck-frame, wheels on the latter and springs yieldingly supporting the body above the frame, of an equalizing device comprising a rock-shaft journaled in bearings on the frame and extending lengthwise of the car beyond both front and rear wheels, and positive or unyielding connections between the ends of said shaft

and the car-body whereby the said body is kept substantially parallel with the rock-shaft.

2. The combination with a car-body, a truck-frame, wheels on the latter and springs yieldingly supporting the body above the frame, of an equalizing device comprising a rock-shaft journaled in bearings on the frame and extending lengthwise of the car beyond both front and rear wheels, crank-arms affixed to the end portions of said shaft, and inflexible or inelastic links positively connecting said arms with the body of the car.

In testimony whereof I have signed my name to this specification, in the presence of two subscribing witnesses, this 25th day of June, A. D. 1895.

JAMES O. BROWN.
